ELECTROMAGNETIC DEVICE AND CIRCUIT
THEREFORGeorge D. Milne, Oak Park, Ill., assignor to
Western Electric Company, Incorporated, New
York, N. Y., a corporation of New York

Application September 8, 1933, Serial No. 688,618

3 Claims. (Cl. 175—337)

This invention relates to an electromagnetic device and circuit therefor and more particularly to an electromagnetic device in which its armature is locked in at least one of its operative positions.

Objects of the invention are to provide a simple, inexpensive and efficient electromagnetic device in which the armature is mechanically locked in one of its operative positions, and to provide a circuit for utilizing a device of this character.

In accordance with the objects, one embodiment of the invention comprises a pair of oppositely disposed electromagnetic units such as relays having their armatures mechanically interconnected and arranged to be locked alternately in their respective attracted positions, the resilient mounting of each armature serving to retain the other in locked position. The device may be used in a circuit including more than one telephone substation, so arranged that the closing of a part of the circuit to one substation will energize one of the relays and disable the other substation from being used during the use of the first substation.

Other objects and advantages will be apparent from the following detailed description taken in conjunction with the accompanying drawing, wherein

30 Fig. 1 is a front elevational view of the electromagnetic device showing the mechanical locking means in one of the locking positions;

Fig. 2 is a top plan view of the device shown in Fig. 1; and

35 Fig. 3 is a simple wiring diagram of a two-station telephone circuit embodying the invention.

Referring now to the drawing, wherein like reference numerals designate similar parts throughout the views, 10 and 11 represent cores having base portions 12 with integral lugs 13 extending at right angles with respect thereto for the purpose of securing the electromagnetic device indicated generally at 14 to a frame or suitable support (not shown). Coils 15 and 16 are mounted upon the cores 10 and 11 respectively and are connected electrically in the circuit shown in Fig. 3, as hereinafter described. The cores 10 and 11 have integral heads 17 and 18 projecting outwardly from the coils 15 and 16 and between which a frame 19 is disposed, the ends of which are secured in any suitable manner to the heads. Armatures 22 and 23, which are U-shaped in general contour, have their lower ends secured to the upper ends of flat

springs 24 and 25 respectively, the lower ends of the springs being fixed to the bases 12 of the cores 10 and 11, allowing sufficient clearance between the lower ends of the armatures and the upper surfaces of the bases to permit actuation of the armatures. Any desired arrangement of spring contacts 27 may be employed. The connecting portions 30 and 31 of the armatures 22 and 23, respectively, are pressed outwardly so that the lugs of the armatures when attracted 10 may be in substantial parallelism with their respective cores, the connecting portions also extending upwardly and having pivotally connected thereto the outer ends of links 32 and 33 respectively. The inner ends of the links 32 and 33 15 are pivotally connected to levers 34 and 35, respectively. The opposite or lower ends of the levers 34 and 35 are fixed to the outer ends of a shaft 36, which extends through the frame 19 and is journaled in a bearing 37 integral there- 20 with.

In the wiring diagram (Fig. 3) there are indicated two telephone substations, one of which may be called a first substation and indicated at 40 and the other may be called a second sub- 25 station and indicated at 41. The electromagnetic device 14 is positioned between the substations in the circuit so that it may electrically connect either substation to the main or incoming line, indicated at 42, and to mechanically lock the 30 circuit closed, thereby excluding the other substation from connection to the line. The coils 15 and 16 are connected at a common point to a conductor 43 of the main line 42, which conductor is also connected to a contact member or 35 switch 44.

A contact 45 is electrically connected to one side of a switch 46 of the substation 40 by a conductor 47, the switch 46 being closed when the receiver is removed. The other side of the 40 switch 46 is connected electrically to the other side of the main or incoming line 42 by means of a conductor 48. A contact 49 is electrically connected to one side of a switch 50 of the substation 41 by means of a conductor 51, while the 45 other side of the switch is electrically connected to the main or incoming line 42 through a conductor 52. The coils 15 and 16 are electrically connected to the conductors 47 and 51, respectively through conductors 53 and 54. When the 50 device 14 is used in a circuit, such as the one just described, the coils 15 and 16 are made with a resistance very high, as compared with that of the substation, and the resistance of each coil may, for example, be of the order of 3000 ohms, 55

the resistance being introduced in any desired manner, for example, by using resistance wire for the winding.

Upon considering the operation of the device, let it be assumed that the receiver of the substation 40 is removed, closing the switch 46 to complete a circuit from the main line through the conductor 48, the switch 46, conductors 47 and 53, coil 15 and through conductor 43 to the main line 42. The energization of the coil 15 will attract the armature 22, causing it to assume a vertical position, as shown in Fig. 1, moving the link 32 to the right and rocking the lever 34 until the center lines of the pivots at the ends of the link 32 are in the same plane or below the center line of the shaft 36, thus mechanically locking the armature 22 in retracted position. The springs 24 and 25 are so formed that they normally urge their armatures away from each other and into open position. Therefore, the springs 25 will aid the movement of the locking mechanism into the position just described, and thus cooperate with the magnetic force of the coil 15 in moving the locking mechanism into this position. The same is true of the spring 24 when the switch 50 is closed.

When the coil 15 is energized, the switch or contact member 44 is moved to the left into electrical engagement with the contact 45 to directly connect the substation 40 with the incoming line 42. While the circuit is closed for the substation 40, a call cannot be completed from the substation 41 for the reason that the coil 16 has a high resistance as compared with that of the parallel circuit through substation 40, so that the current through substation 41 has a very low value insufficient to unlock the relay. The operating direct current is, of course, derived from a central battery at the distant end of the subscriber's line, the latter having a resistance which may be of the order of 1000 or 2000 ohms.

Furthermore, the party attempting a call over substation 41 cannot listen to the conversation taking place over substation 40, even though a circuit is completed to electrically connect substation 41 with substation 40 and the line. Each substation has a resistance of approximately 43 ohms, whereas each coil 15 and 16 has approximately 3000 ohms resistance, making it impossible for the conversation taking place over substation 40 to be heard intelligibly over substation 41.

After the party has finished his call from substation 40 and has replaced the receiver on the

hook, the device remains mechanically locked so that a second call over substation 40 may be made and the device will remain in locking position until a call is made over substation 41 at a time when substation 40 is open circuited. The same is true of substation 41 in that when a call is made from this substation, the coil 16 is energized, completing a circuit from the incoming line 42, through the conductor 52, switch 50, conductors 51 and 54, through the coil 16 and the conductor 43 to move the armature 23 to the left into locking position and release the lever 34 so that the armature 22, forced by the spring 24, will aid in moving the lever 35 into locking position.

What is claimed is:

1. An electromagnetic device comprising a pair of coils, an armature for each coil, a rigid base disposed beneath each armature, resilient members connecting each armature to its base to permit movement of the armatures when attracted by their coils, and means for operatively connecting the armatures together for locking the attracted armature in attracted position and the other in retracted position, said resilient members being flexed to move the armatures in opposite directions so that the resilient members of the unattracted armature will assist in moving the armatures into their locked positions.

2. An electromagnetic device comprising a pair of coils, an armature for each coil mounted for movement, a shaft disposed between the armatures, levers mounted upon the ends of said shaft, and links operatively connecting said levers to said armatures so that the energization of one of the coils will attract its armature to move the link and lever thereof to dead center positions to lock the armatures in position.

3. An electromagnetic device comprising a pair of coils, an armature for each coil mounted for movement, a shaft disposed between the armatures, levers mounted upon the ends of said shaft, and links operatively connecting said levers to said armatures so that the energization of one of the coils will attract its armature to move the link and lever thereof to dead center position to lock the armatures in position, said connecting means being such that the energization of the other coil will attract its armature to move its link in the opposite direction, moving the connecting means out of the first locking position and into a second locking position.

GEORGE D. MILNE.
